UNITED STATES PATENT OFFICE.

THOMAS RITCHIE AND ROBERT H. RITCHIE, OF OSKALOOSA, IOWA.

HYDRANT.

Application filed March 4, 1927. Serial No. 172,695.

Our invention relates to hydrants of the general type, which include a valve adapted to be set below the frost line in the ground and means for operating the valve from above the ground.

It is the object of our invention to provide in such a hydrant a novel valve casing and valve and valve stem structure combined with a pipe leading to a discharge pipe and 10 to provide a valve operating means, the parts being so arranged that the valve may be operated above the ground in a simple and effective way.

One of the purposes of our invention is to 15 provide a novel valve casing and valve provided with drainage means, such that when the valve is closed, the pipe above it will readily drain, the parts being so arranged that when the valve is opened, the drainage passages are automatically closed by the valve.

Another object is to provide such a structure in which the valve and stem may be readily drawn out without interfering with the valve casing.

25 A special object of our invention is to provide a valve and valve stem operating mechanism of simple and efficient structure, whereby the valve stem may be raised and lowered vertically without binding.

30 Another object in this connection is to provide an operating lever and parts so arranged that when the valve is closed, the parts will be locked in position for maintaining the valve closed.

35 Still a further purpose of our present invention is to provide a very simple structure which affords accurate and easy adjustment of the parts at a point above the ground for insuring the proper seating of the valve.

40 With these and other objects in view, our invention consists in the construction, arrangement and combination of the various parts of our hydrant, whereby the objects contemplated are attained, as hereinafter 45 more fully set forth, pointed out in our claims, and illustrated in the accompanying drawings, in which:

Figure 1 is a side elevation of a hydrant embodying our invention.

50 Figure 2 is a vertical, sectional view through the same.

Figure 3 is a vertical, sectional view of the hydrant, showing the parts in a different position from that illustrated in Figure 2.

55 Figure 4 is a transverse, sectional view

through the valve casing taken on the line 4-4 of Figure 2; and

Figure 5 is a detail, sectional view through the valve operating lever and its mounting taken on the line 5-5 of Figure 2.

In the accompanying drawings, we have used the reference numeral 10 to indicate the earth in which the lower part of our improved hydrant is set. For convenience, we have shown the frost line 12 as indicating the maximum depth to which the ground is likely to freeze.

A water supply pipe 14 is illustrated as connected with the lower end of the valve casing 16 set below the frost line. This valve 70 casing 16 is shown in Figures 1, 2 and 3 and comprises a substantially tubular member having a bore 18 extending longitudinally through it. The lower end of the valve casing 16 is internally screw-threaded as at 20 75 to receive the end of the supply pipe 14.

The upper end of the casing 16 is internally screw-threaded as at 22 to receive the lower end of the water conducting pipe 24 leading upward through the ground to the discharge 80 spout.

In the lower part of the valve casing 16 is an annular valve seat 24. A valve 26 of any suitable material, preferably rubber, is slidably mounted in the casing 16 in such manner 85 as to coact with the seat 24. The valve 26 is preferably mounted on the lower end of a valve stem or operating rod 28, which extends through the valve as shown in Figure 3. The lower end of the stem or rod 28 is screw-threaded as at 30 and receives a small nut 32 below the valve and a nut 34 above the valve, whereby the valve is held properly located on the stem.

The bore 18 is of less diameter than the 95 threaded portions 20 and 22.

On the interior of the casing 16, we provide a plurality of vertical grooves 36, which extend from the seat 24 upwardly to the threaded portion 22. Thus when the valve 26 is raised off its seat 24, water may flow from the pipe 14 past the seat 24 and upwardly through the grooves 36.

The casing 16 is provided with a plurality of transverse drainage holes 38 alternating with the grooves 36 and arranged in a series horizontally around the casing at such a height that when the valve 26 is seated, it clears the drainage holes 38, but when the valve is raised, it closes these drainage holes. 110

When the valve is in its open position, water will flow upwardly around the valve through the grooves 36 and no water can flow out through the drainage holes 38.

- 5 The wall of the casing 16 is of such thickness as to permit the grooves 36 to be of substantial width and depth, so as to allow the passage of a substantial volume of water when the valve is unseated.
- 10 At the upper end of the pipe 14 is mounted a spout fixture, indicated generally at A, having the tubular portion 40 into which the upper end of the pipe 14 is screwed as at 42 and having the spout 44.
- 15 Projecting from the tubular portion 40, preferably on the side opposite the spout, we provide a pair of lugs or ears 46. Mounted in the ears 46 is a pin 48 on which is eccentrically, rotatably mounted a disc 50 having 20 at its ends circumferential rabbets 52.

Formed on the disc 50 is a handle 54.

A pair of parallel arms 56 are provided at their lower ends with annular holes 58 to receive the sides of the disc 50, whereby the 25 arms 56 are rotatably mounted on the disc 50 between the ears 46.

The stem or rod 28 extends upwardly through a hole 60 in the upper part of the tubular portion 40 of the spout structure A. 30 Above the hole 60 is an enlarged bore 62 to receive packing 64 and a packing nut 66.

On the spout 44 are upwardly extending ears 68. A pin 70 is mounted in the ears 68 and extends between them and a link 72 is 35 pivoted on the pin and extends upwardly as shown in Figure 2. A rocking bar 74 has the link 72 pivoted as at 76 between its bifurcated arms 78 at one end and has the upper ends of the arms 56 pivoted as at 80 between the arms 82 of its other bifurcated end.

The rocking bar 74 has about midway between its ends a vertical bore 84, which has substantially the form of a venturi with a relatively contracted waist in the middle and 45 with gradual enlargement of the opening toward both ends.

Received in the opening 84 is a sleeve 85. The stem 28 projects through the sleeve 85 and has a screw-threaded end 86 on which 50 are mounted adjustable nuts 88 and 90 below and above the sleeve.

We will now explain the practical operation and some of the advantages of our improved hydrant.

55 Referring to the valve and valve casing, it will be noted that we have provided a single casing and a single valve, so that this portion of the structure is very simple and cheap. The one casing is connected at its 60 ends with the supply and discharge pipes. It affords drainage means and a valve seat. A single valve controls the water inlet and the drainage openings. The parts are so arranged that the interior of the valve casing 65 and the outlet pipe from the casing are of

such relative sizes as to permit the valve to be drawn from the casing into the pipe for removal, for purposes of repair or for replacement.

By simply unscrewing the member 40 from the pipe 24, the spout structure and the valve may be taken off.

The structure for operating the valve stem is such as to permit ample movement. The parts are so arranged that the valve stem 75 can move vertically without binding. The sleeve 85 prevents any binding between the bar 74 and the nuts 88 and 90. A very slight adjustment of those nuts allows for adjustment of the valve with great accuracy.

80 The arrangement of the eccentric in connection with the handle 54 provides for tremendous leverage so that no difficulty is incurred in operating the valve. The mechanism for operating the valve is very simple 85 and inexpensive to make and is easy to install or disassemble.

Changes may be made in the details of the construction and arrangement of the parts of our improved hydrant, and it is 90 our intention to cover by our claims any modified forms of structure or use of mechanical equivalents, which may be reasonably included within their scope.

We claim as our invention:

95 1. In a hydrant structure, a valve casing, a valve seat on its interior, a valve in the casing for coacting with said seat, a stem extended from said valve and means for actuating said valve comprising a rocking bar pivoted at one end, a link pivoted at one of its ends to the other end of the rocking bar, means for rocking said bar comprising a pivoted handle, an eccentric disk on said handle, an opening in the other end of said link for rotatably receiving said eccentric and means on said stem adapted to be engaged by the rocking arm for closing and opening said valve upon swinging movement of said handle.

100 2. In a hydrant structure, a tubular valve casing having threaded connections at its ends with supply and discharge pipes and having a valve seat on its interior, a spout structure connected with the discharge pipe, a valve in the casing for coacting with said seat, a stem extended from said valve through the discharge pipe, the interior of the casing and the discharge pipe being of such relative sizes that the valve may be withdrawn 105 through the pipe, said casing having on its interior waterflow grooves in its walls, said stem extending slidably through the spout structure, a link pivoted to said spout structure, a rocking bar pivoted to said link having an opening through it, said stem being extended through such opening, a sleeve in the opening on the stem, adjustable nuts adjacent the ends of said sleeve, and means for rocking said bar.

110 3. In a hydrant structure, a tubular valve 115

casing having threaded connections at its ends with supply and discharge pipes and having a valve seat on its interior, a spout structure connected with the discharge pipe, 5 a valve in the casing for coacting with said seat, a stem extended from said valve through the discharge pipe, the interior of the casing and the discharge pipe being of such relative sizes that the valve may be withdrawn 10 through the pipe, said casing having on its interior waterflow grooves in its walls, said stem extending slidably through the spout structure, a link pivoted to said spout structure, a rocking bar pivoted to said link having an opening through it, said stem being extended through such opening, a sleeve in the opening on the stem, adjustable nuts adjacent the ends of said sleeve, and means for rocking said bar, comprising an arm, an eccentrically mounted disc rotatably mounted in 15 said arm, and a handle on said disc.

4. In a hydrant structure, a valve casing, a valve therein, a discharge pipe connected with said casing, a spout structure on said 20 discharge pipe, a stem on said valve extended through said pipe and spout structure, a link pivoted to said spout structure, a rocking bar pivoted at one end to said link, an arm pivoted to other end of the rocking bar, 25 a disc eccentrically mounted on the spout structure and rotatably mounted in said arm, a handle fixed to said disc, said rocking bar having a hole extending through it receiving said stem, a sleeve on said stem in said hole, 30 and adjustable nuts on the stem at the ends 35

of the sleeve, whereby the nuts may be adjusted on the stem without binding the rocking bar.

5. In a hydrant structure, a fluid supply pipe, a valve casing connected therewith having a valve seat, a discharge pipe communicating with the casing having a closed end and a spout, a valve slideable in the casing, a stem extending from the valve slideable through such closed end, having enlarged portions on its part beyond the discharge pipe, a rocking arm loosely mounted on said stem between said enlarged portions, a link pivoted to one end of said arm and to a fixed part of the hydrant, a fixed 45 bracket, a disc eccentrically journaled on said bracket, a controlling arm for the disc and a link pivoted to the other end of said rocking arm and journaled on said disc.

6. In a hydrant structure, a fluid supply 50 pipe, a valve casing connected therewith having a valve seat, a discharge pipe communicating with the casing having a closed end and a spout, a valve slideable in the casing, a stem extending from the valve slideable through 55 such closed end, a fixed bracket, a disc eccentrically journaled on said bracket, a controlling arm for the disc, a link having an opening to fit the periphery of said disc, and means for operatively connecting said link 60 with the valve stem.
